SEWING MACHINE

Mario Buono, New York, N. Y., assignor to U. S. Blind Stitch Machine Corp., New York, N. Y., a corporation of New York

Application June 21, 1949, Serial No. 100,363

5 Claims. (Cl. 112—176)

1

This invention relates to improvements in a chain-stitch, blind-stitch, skip-stitch, sewing machine, of the type illustrated in U. S. Patents No. 1,926,644 and No. 1,926,761, dated September 12, 1933 and No. 2,108,100, issued on February 13, 1938.

A machine of this type has a curved needle, whose holder is pivoted to the frame of the machine and which is oscillated laterally around a longitudinal and horizontal axis; a work-support or work-table which is pivoted to the frame of the machine and which is rocked or oscillated about a horizontal lateral axis, so that the longitudinal arm of said work-support is moved up-and-down relative to the lateral path of the needle; and a rib or bight-forming member which is pivoted to said work-support on a lateral axis; said rib being rocked or oscillated relative to said work-support in order to form a bight in the layers or plies of cloth. When said layers of cloth are of sufficient thickness, the needle penetrates the top layer of cloth in said bight between its top and bottom faces, thus forming a blind-stitch which is invisible at the fair or exposed face of the garment or other sewed article. When the layers of fabric are thin, the needle will penetrate the top layer through-and-through, but such stitch is designated as a "blind stitch" in the trade. Said prior patents disclose mechanism for making skip-strokes, whereby the stitches skip the layer next to the top layer of the bight in predetermined succession, thus tacking the top layer of the bight to the next layer only at every second or third stitch, or in any other desired relation.

For certain purposes, it is highly desirable to control such machine during its operation, so that it will tack the top layer to the next layer or layers, either by skip-strokes, or by a plurality of consecutive tacking strokes of any desired number which connect said top layer to the next layer or layers. For this purpose, I provide mechanism whereby the rocking movement of the work-table can be controlled while the machine is running or stationary.

Since many of the parts of said machine are well-known and disclosed in said prior patents, the disclosure herein does not include many of said well-known parts.

Other objects and advantages and features of my invention are set forth in the annexed description and drawings which illustrate a preferred embodiment thereof.

Fig. 1 is a transverse section along the line 1—1 of Fig. 7, partially in elevation, which shows certain essential parts of the machine. In

2

Fig. 1 the arm 54, which is later described, is shown in its full-line position of Fig. 8, in which the machine operates to form skip-strokes;

Fig. 2 is a section on the line 2—2 of Fig. 7, showing certain of the parts illustrated in Fig. 1. In Fig. 2, the arm 54 is shown in its broken-line position of Fig. 8, in which the machine operates to form consecutive or non-skip strokes;

Fig. 3 is a vertical section taken at the stitching station of Fig. 2, illustrating the formation of a non-skip stitch, in which the needle passes through both layers of cloth which are to be sewed to each other;

Fig. 4 is a view similar to Fig. 3 illustrating the formation of a skip stitch, in which the needle passes only through the top cloth layer;

Fig. 5 is a perspective view, showing a piece of fabric which has been folded in order to provide a flap which overlies the body of said piece of fabric; and it illustrates the formation of skip stitches in sewing said flap to said body;

Fig. 6 is a section along the line 6—6 of Fig. 5; Fig. 7 is a section on the line 7—7 of Fig. 1; Fig. 8 is a section on the line 8—8 of Fig. 1;

Fig. 9 is a section on the line 9—9 of Fig. 1; Fig. 10 is a section on the line 10—10 of Fig. 7; Fig. 11 is a section on the line 11—11 of Fig. 7; and

Fig. 12 is an exploded perspective view illustrating certain parts of the machine.

The machine has a frame 1, to which the work-support or work-table 36 is pivotally connected by a lateral pivot 37. Said work-support 36 has a top longitudinal arm, along which the work is fed longitudinally, in the direction of the arrow shown in Fig. 1.

The usual rib R is turnably connected to work-support 36 by a lateral pivot 66. The machine has the usual curved needle N and looper L.

As viewed in Fig. 1, the work-support 36 is biased to turn counter-clockwise around its lateral pivot 37 relative to frame 1, by means of a longitudinal tension spring 40. As shown in Fig. 1, the rear end of tension spring 40 is connected to a longitudinal adjusting screw 41, which extends through a tapped bore of frame 1. This screw 41 is longitudinally adjusted to regulate the tension of spring 40. Screw 41 is releasably fixed in its adjusted position by a lock nut 42. The front end of tension spring 40 is connected to a longitudinal rod 43, which is shown in broken lines in Fig. 1. The depending arm of work-support 36 has a longitudinal tapped bore, through which an adjustable screw 44 extends. After being longitudinally adjusted, said screw 44 is fixed in its

adjusted position by a clamping screw 45. The rear end of screw 44 engages the internal thread of a recess at the front end of rod 43. The tension of spring 40 can also be regulated by means of front screw 44.

The machine has the usual lateral main shaft 2, which is revolved in the usual manner. As shown in Fig. 7, the hub of a collar 3 is releasably fixed to shaft 2 by clamping screws 4. As shown in Fig. 12, said collar 3 has a radial lug or key 5. Fig. 12 shows one of a pair of spacer plates 6, both said plates 6 being shown in Fig. 7. When the machine is operated, the plates 6 are not rotated about the axis of shaft 2. As shown in Fig. 12, a gear 7 has a hub 8 which has a recess or slot 8a. This hub 8 extends through the opening of the respective plate 6, and said key 5 of collar 3 engages said recess 8a, so that gear 7 is rotated in unison with shaft 2. As shown in Fig. 12, gear 7 has a lateral lug 10. This lug 10 extends through a slot or recess 11 of a collar 12, which is fixed to a ring 51. Said collar 12 is fixed to or integral with an eccentric 14, so that eccentric 14 is rotated in unison with shaft 2. Conventional means are provided for preventing eccentric 14 from shifting relative to shaft 2, so that the assembly shown in Fig. 7 is maintained. The eccentric 14 is rotatable relative to a collar 16a, which is fixed to arm 15, so that the rotation of shaft 2 moves arm 15 up-and-down. Said arm 15 operates the usual feed-dog of the machine, by the usual connections. Said feed-dog and said connections are not shown, because they are conventional and well-known per se.

Fig. 7 shows depending identical arms 16 and 16a, which are connected to each other by lateral bolts 17 and 18, and also by a top longitudinal bar 19, which is also shown in Fig. 1. As also shown in Fig. 1, the top of each said arm 16 and 16a has a rectangular cut-out, 16b whose vertical walls slidably abut the vertical walls of the two spacer plates 6, which guide the arms 16, 16a in their up-and-down movement. Fig. 2 shows bolt 47 in full lines at the top of the vertical stroke of arms 16, 16a, and it also shows, in broken lines, the position of bolt 47 at the bottom of said vertical stroke, and in another position between said top and bottom positions. The arms 16, 16a are turnably connected by bottom bolt 18 to a lever 19, which is rocked up-and-down relative to the axis of a lateral fulcrum pivot 20, which turnably connects the oscillating lever 19 to a manually adjustable lever 21. Fig. 2 shows the lever 19 at the end of its upward rocking or oscillating movement in full lines, and shows said lever 19 at the end of its downward rocking or oscillating movement in broken lines.

The oscillating lever 19 is turnably connected by a pivot 24 to a rod 25, which is guided for longitudinal reciprocating movement in a bore of the frame 1. Said rod 25 has a transverse pin 27. The front end of a helical compression spring 26 abuts frame 1, and the rear end of compression spring 26 abuts pin 27, so that rod 25 is biased rearwardly, away from the depending arm of work-support 36.

When rod 25, during its forward stroke, rocks the work-support 36 clockwise around its pivot 31, against the force of tension spring 40, the top longitudinal arm of work-support 36 is depressed, thus producing a skip-stitch. As later described, means are provided whereby the forward stroke of rod 25 may or may not rock the work-support 36.

As shown in Fig. 7, a large driven gear 46, 75

which is always in mesh with the small driving gear 7, is fixed by a rivet or other fastening member to an eccentric 50. Driven gear 46 and eccentric 50 are fixed to a bushing 48, which is freely turnable on bolt 47. The periphery of eccentric 50 is eccentric relative to the axis of bolt 47. The teeth of large driven gear 46 may be on a pitch circle which is eccentric relative to said axis of bolt 47. The ring 51, whose periphery may be concentric with the axis of shaft 2, always abuts the periphery of eccentric 50. Hence ring 51 and eccentric 50 move the arms 16, 16a up-and-down in a stroke of fixed length.

The ratio of the pitch circles of gears 46 and 7 may be any desired ratio, as two-to-one, three-to-one, etc. Hence, when skip-stitching is desired, alternate stitches may be skipped or two stitches may be skipped between consecutive tacking stitches, etc.

As shown in Figs. 8 and 9, a lateral shift rod 52 extends slidably through a lateral guide bore of work-support 36. As shown in Fig. 8, one end of a lateral compression spring 53 abuts the inner face of work-support 36 and the other end of said compression spring 53 abuts a shoulder 52a of said shift rod 52, so that, as viewed in Figs. 8 and 9, said shift rod 52 is biased to the right.

As shown in Figs. 8 and 9, and also in Figs. 1 and 2, an arm 54 is pivoted to work-support 36 by a longitudinal pivot 55, so that arm 54 is located at the inner face of the front depending arm of work-support 36, and arm 54 can be turned in a lateral plane around pivot 55.

As shown in Fig. 8, said arm 54 has a lateral recess 56 in which the lug 56a of an arm 57 is located. Said arm 57 is turnably connected to work-plate 36 by a longitudinal pivot 58.

As shown in Fig. 8, the arm 54 is bent at 54b so as always to clear the longitudinal rod 23, whose function is later explained. When arm 54 is in the full-line position of Fig. 8, the machine is set for skip-stitching. When arm 54 is in the broken-line position of Fig. 8, the machine is set for continuous tacking or non-skip-stitching.

As best shown in Figs. 1 and 2, the upper end of arm 57 has a downwardly bent flange or head 57a. Said flange 57a is turnably connected to said lateral rod 52 by a pivot-screw 59, which is provided with a lock-nut 60.

The compression spring 53 normally maintains arm 57 in the position in which its lug 56 and recess 56a of arm 54, maintain arm 54 in its broken-line position of Fig. 8, in which the machine is set for non-skip-stitching, in order to form the stitches 71 which are shown in Figs. 3 and 6.

The shift rod 52 is manually shifted or operated to turn arm 57 to a position in which it turns arm 54 to the full-line skip-stitch position of Fig. 8, in which the lower end 54a of arm 54 is aligned with the longitudinally reciprocated rod 25.

Referring to Figs. 8 and 9, the shift rod 52 is laterally shifted or operated to turn arm 57 to adjust arm 54 to its skip-stitch position by a hand-operated lever 61, which is turnably connected to shift-rod 52 by a pivot 62. A roll 63 is rotatably connected to lever 61 by a suitable pivot. Said roll 63 abuts the respective lateral depending arm of the work-support 36. When lever 61 is in its upstanding broken-line position of Fig. 8, arm 54 is in its broken-line and non-operating position of Fig. 8, and arm 57 is in its broken-line position of Fig. 8. When lever 61 is turned down to its full-line position of Fig. 8, the roll 63 is laterally and horizontally aligned

with pivot 62, so that lever 61 is maintained in said full-line position. During said downward turning movement of lever 61, the shift rod 52 is moved outwardly or to the left as viewed in Fig. 8 against the force of spring 53 and the flange 57a of arm 57 is moved from its broken-line position of Fig. 8 to its full-line position of Fig. 8, thus turning arm 57 counterclockwise as viewed in Fig. 8, and thus simultaneously turning arm 54 clockwise as viewed in Fig. 8, to the full-line or skip-stitch position of arm 54 from its broken-line or non-skip-stitch position. Hence, when lever 61 is in its vertical, broken-line position of Fig. 8, arm 57 is also in its broken-line position of Fig. 8, arm 54 is also in its broken-line position of Fig. 8, and the machine is set to form the non-skip stitches 71 which are shown in Figs. 3 and 6. When lever 61 is in its full-line position of Fig. 8, arms 57 and 54 are in their respective full-line positions of Fig. 8, and the machine is set to form the skip-stitches 70, which are shown in Figs. 5 and 6.

When the lever 54 is in its broken-line or non-skip stitch position of Fig. 8, the stroke of reciprocating rod 25 is insufficient to rock the work-support 36, and the rib R can form a bight as shown in Fig. 3, in which the curved needle N, which oscillates in the lateral path T, pierces the layers of fabric to form a tacking or non-skip-stitch 71 through both layers of fabric 69 and 68.

If the bottom layer 68 is sufficiently thick, this will form a blind stitch 71 in such bottom layer of fabric 68. If bottom layer 68 is sufficiently thin, said tacking stitch 71 will be visible at the bottom face of layer 68.

When arm 54 is in its full-line position of Fig. 8, each forward longitudinal stroke of reciprocating rod 25 will cause said rod 25 to strike the bottom end 54a of arm 54, thus temporarily depressing the top of work-support 36, so that the bight is formed as shown in Fig. 4, thus forming a non-tacking or skip-stitch 70, which may be a blind stitch in top layer 69, if said top layer 69 is sufficiently thick. If layer 69 is sufficiently thin, the stitch 70 will not be a blind stitch.

As shown in Fig. 2 and previously noted, the fulcrum of the oscillating lever 19 is the pivot 20 of a lever 21. Said lever 21 is turnably connected by a pivot 30 to the frame 1 of the machine, and said lever 21 has a rigid and integral finger 21a. As shown in Fig. 2, said lever 21 is turnably connected by a pivot 22 to a longitudinally slideable rod 23, which is guided in a bore of the frame 1. Said rod 23 has a transverse pin 29. As best shown in Fig. 1, a compression spring 28 has one end thereof abutting frame 1, and its other end abutting pin 29, so that rod 23 is biased rearwardly, and lever 21 is biased to turn counterclockwise, as viewed in Fig. 1. This rod 23, which is a stop rod, is aligned with a stop-screw 38, which extends longitudinally and adjustably through a tapped bore of work-support 36. The screw 38 is held in its adjusted position by a lock nut 39. As above noted, tension spring 40 biases work-support 36 to turn counter-clockwise, as viewed in Fig. 1. By longitudinally adjusting stop-rod 23, the normal height of the top arm or plate of work-support 36 can be adjusted.

As shown in Fig. 1, the rigid finger 21a of lever 21 is located between the arms 32 of a fork-shaped member. These arms 32 have tapped bores, through which an adjusting screw 33 extends. Said screw 33 has a smooth shank-part which fits turnably in a bore of frame 1. Said screw 33 is fixed to an external knob 34, which turnably

abuts frame 1, and which has a knob 35. The lever 21 can thus be manually turned in order to regulate the depth of the stitch, in forming either type of stitch shown in Figs. 3 and 4.

The adjustment of lever 21 will alter the length of the reciprocating stroke of rod 25. This change of the length of the stroke of rod 25 may be slight and negligible, or substantial.

The machine is provided with the usual slotted 10 needle plate 67, which is fixed to frame 1, and through whose slot the bight of the work extends when a stitch is formed.

The machine also has the usual mechanism 15 for oscillating rib R relative to work-support 36, in unison with the needle.

The fabric is fed longitudinally and rearwardly over the top arm or plate of work-support 36, in the direction of the arrow shown in Fig. 1.

While a preferred embodiment of the invention 20 has been disclosed, numerous changes and omissions and additions can be made without departing from its scope.

I claim:

1. In a chain-stitch sewing machine of the 25 type which has a frame and a work-support pivotally connected to said frame by a lateral pivot and a rib which is pivotally connected to said work-support by another lateral pivot and a needle which is mounted to oscillate above said work-support and rib in a lateral path and in which said work-support has a top work-supporting arm and front depending arm and in which a spring is connected to bias said work support to normal position against a stop to provide tacking 30 stitches between superposed layers of cloth when said work-support is in said normal position and to provide skip-stitches when said work-support is rocked relative to said frame against the force of said spring to lower said top work-supporting arm, the combination of a longitudinal actuating rod located rearwardly of said front depending arm and guided for longitudinal reciprocating movement in said frame, operating means for longitudinally reciprocating said longitudinal actuating rod in a stroke of selected length, an abutment arm pivotally connected to said depending arm at the inner face of said depending arm and located below the first-mentioned pivot, said abutment arm being movable to an operating position in which it is aligned with said actuating rod below said first-mentioned pivot, said abutment arm being movable to a non-operating position in which it is out of the path of movement of said actuating rod, said abutment arm being sufficiently thick to be struck by said actuating rod during its forward movement when said abutment arm is in said operating position to thus rock said work-support, said stroke being sufficiently short so that said actuating rod remains out of contact 40 with said depending arm when abutment arm is not in operating position.

2. A combination according to claim 1, in which said depending arm is laterally disposed, and said abutment arm is turnable in a lateral plane relative to said depending arm.

3. A combination according to claim 1, in which said depending arm is laterally disposed, and said abutment arm is turnable in a lateral plane relative to said depending arm, said abutment arm having a recess, a second arm pivoted to said depending arm at its inner face and having a lug which is located in said recess, a laterally slideable rod mounted slidably in said work-support, said rod being pivotally connected to said second arm,

said rod extending exteriorly of said work-support.

4. A combination according to claim 1, in which said depending arm is laterally disposed, and said abutment arm is turnable in a lateral plane relative to said depending arm, said abutment arm having a recess, a second arm pivoted to said depending arm at its inner face and having a lug which is located in said recess, a laterally slidable rod mounted slidably in said work-support, said rod being pivotally connected to said second arm, said rod extending exteriorly of said work-support, a compression spring mounted on said rod and biasing said abutment arm to non-operating position, a hand-operated lever external to said work-support, said hand-operated lever being pivotally connected to said rod externally of said work-support, a roll connected to said lever and contacting movably with the external face of said work-support, said lever having an upstanding position which corresponds to said non-operating position, said lever being operative to move said rod outwardly relative to said work-support

to shift said abutment arm to its operating position when said lever is turned down.

5. A machine according to claim 1, in which said operating means include a link which is pivoted to an adjustable lever to provide a fulcrum for said link and means for vertically oscillating said link, said link being pivotally connected to said actuating rod, a longitudinal stop rod pivotally connected to said adjustable lever, said stop rod being longitudinally movable and being adapted to stop the rocking movement of said work-support under the force of said spring, and means for adjusting said lever.

MARIO BUONO.
